UNITED STATES PATENT OFFICE.

RAYMOND H. GARMAN, OF WILMETTE, ILLINOIS.

PICTURE-LEAF.

1,033,576.

Specification of Letters Patent. Patented July 23, 1912.

Application filed February 3, 1912. Serial No. 675,392.

To all whom it may concern:

Be it known that I, RAYMOND H. GARMAN, a citizen of the United States, residing at Wilmette, in the county of Cook and 5 State of Illinois, have invented certain new and useful Improvements in Picture-Leaves, of which the following is a specification.

This invention relates to leaves or pages upon which illustrations are imprinted, and 10 which may, if desired, be arranged in loose or permanent binding.

The objects of the present invention are to provide an attractive picture leaf designed principally for the amusement of the 15 young people, which embodies means for altering or interchanging parts of the illustrations thereon; to devise a leaf of the above character which is both simple and substantial; and to provide with an arrangement of such leaves, in book form if preferred, a suitable pocket for holding the interchangeable parts of the picture leaves.

Other objects of my invention will appear from a detailed description of the drawing 25 and operation of the parts as hereinafter set forth and claimed.

In the drawing, Figure 1 is a perspective view of a number of picture leaves of my invention bound in book form; Fig. 2 is a 30 detail of a single leaf showing the interchangeable members in position therein; Fig. 3 is a perspective of one of the interchangeable members; Fig. 4 is a side elevation of one of said members; and Fig. 5 is a 35 perspective of a book of picture leaves shown in open position.

In the drawing there is represented a series of picture leaves 6 having flower pictures 7 thereon, the portions 8 of the leaves 40 upon which the flower pistils would appear being cut out so that such parts are open. Suitable members 9 having appropriate illustrated features thereon are adapted to fit within the cut out portions 8 of the 45 leaves, the face side of said members lying substantially flush with the face side of the leaves. In order that the said members may lie in such flush relation, the edges 10 thereof may be beveled to contact similarly 50 formed edges in the cut out portion of the leaves. Other suitable means for thus positioning the members in place may obviously be employed, as by providing the cut away portion of the leaves and the edges of the 55 members with straight instead of beveled edges, and arranging a suitable flange on either side of said member to aline the same properly in position; or by arranging such flange on either side of the leaves at the cut away portions to determine the position of the members therein.

The leaves as shown in Figs. 1 and 5 may be conveniently arranged within a cover 11 so as to constitute a book. A pocket 12 is shown on such a cover within which the 60 members 9 may be placed when the leaves are not put to use. Obviously such pocket may be attached to each leaf instead of to the cover within which it is bound.

In the figures of the drawing, the members 9 are shown with facial pictures thereon, which, according to the fancy of the user, may be inserted within the center portion of any of the flowers; and it is obvious that by providing a number of such members 75 having faces differing in expression, color, etc., that a number of interesting combinations may be made.

In the present invention a variety of kinds of illustrations may be used, and each leaf 80 may be arranged according to the kinds or classes of pictures illustrated thereon. For instance, upon one leaf there may be imprinted animal pictures with a portion of each cut out and adapted to receive appropriate members; another leaf may contain doll pictures, and so on, and so forth. The cut out portion 8 need not necessarily be circular or oval in shape as is illustrated in the 85 figures, but may be of any desirable contour, regular or otherwise. Although the members are shown and described as interchangeable with respect to the cut out portions of the leaves, this manner of arranging the pictures need not necessarily be followed, since it is obvious that each picture 90 may be arranged for the insertion of but one particular member. The materials of which the picture leaves and insertible members should preferably be made have not been 95 heretofore specified, since it is evident that paper, cardboard, wood, various compositions, etc., will answer my requirements. Furthermore, no mention as to the thickness 100 of the leaves has been made for the reason that such a question must obviously be determined according to what is found to be most desirable in constructing picture leaves embodying the features of the present invention.

I claim:

1. An illustrated leaf having an open-

ing therein, a member adapted to seat within said opening, said member being of a decorative character to produce, when in position, an additional element to the illustration, and means for centering said member in said opening, substantially as described.

2. An illustrated leaf having an opening therein, and a member having one face of larger area than the other adapted to seat 10 within said opening, said member being of a decorative character to produce, when in position, an additional element to the illustration, substantially as described.

3. An illustrated leaf having an opening 15 therein, and a member adapted to seat within said opening and of similar shape thereto, said member being of a decorative character to produce, when in position, an additional element to the illustration, substantially as 20 described.

4. An illustrated leaf having an opening therein, and a member provided with beveled edges adapted to seat within said opening, said member being of a decorative character to produce, when in position, an additional element to the illustration, substantially as described. 25

5. An illustrated leaf having an opening therein and a member adapted to seat entirely within said opening, the face of said 30 member lying substantially flush with the face of the leaf, said member being of a decorative character to produce, when in position, an additional element to the illustration, substantially as described.

RAYMOND H. GARMAN.
